K. E. STUART,
PHOTOGRAPHY IN COLORS.
FILED FEB. 7, 1920.

INVENTOR
Kenneth E. Stuart

UNITED STATES PATENT OFFICE.

KENNETH E. STUART, OF MERION, PENNSYLVANIA.

PHOTOGRAPHY IN COLORS.

Application filed February 7, 1920. Serial No. 356,934.

To all whom it may concern:

Be it known that I, KENNETH E. STUART, residing at Merion, in the county of Montgomery and State of Pennsylvania, have invented certain new and useful Improvements in Photography in Colors, of which the following is a specification.

More particularly, my invention relates to the method of color photography which depends upon interposing between the sensitive emulsion and the camera lens a transparent screen formed by a multitude of suitably colored particles or lines in juxtaposition and making the photographic exposure through said screen, whereby the light is subjected to selective absorption before reaching the sensitive emulsion. As this process is well-known, I need not describe it further. My invention consists in a more advantageous selection of colors for said screen than has heretofore been known and in an improved method of applying them.

Figs. 1, 2, 3, and 4, are diagrams illustrating respectively the colors chosen and the method of applying them in four typical embodiments of my invention. Fig. 5 illustrates diagrammatically the spectra of the colors used in Fig. 4. Fig. 6 illustrates still another embodiment of my invention. It is to be understood that these colors are to be applied in the form of transparent bands to a suitable transparent back or support, as of glass or celluloid (not shown).

It has heretofore been customary to use for the purposes of photographic color screens, such combinations as red, yellow and blue or red, green and blue-violet. The consequence of this is that if a red area should accidentally overlap a green or blue area little or no light can pass through them and the result is a dark spot. Such spots are often sufficient to ruin an otherwise fine photograph. In the case of ruled screens, the overlap of the rulings results in dark lines which give rise to diffraction effects. The extreme care necessary to avoid these dark spots or lines makes the manufacture of such plates expensive. The essential principle of my invention is the employment of colors any two of which may be super-posed without causing total absorption or black spots and which are in fact intended to be so used.

Referring now to Fig. 1, O, O indicate two of a series of bands (the width being greatly exaggerated), consisting of any suitable vehicle, such as Canada balsam, gelatine, etc., and dyed such a color as will transmit substantially all light rays from the red end of the spectrum to and including yellow. The color effect of such a band to the eye will be orange. P, P indicate similar bands transmitting principally the red, blue and violet rays. These bands will appear purple or magenta. It will be noticed that they overlap the orange bands for one half of their width. Where such overlap occurs, the blue, yellow and violet rays will be absorbed, leaving only the red rays which may pass both bands. G, G indicate similar bands transmitting substantially all light from yellow to blue inclusive. These bands will appear green. They overlap the orange bands for one half of their width and the purple bands for the remainder of their width. Where the green bands overlap the orange the result will be a line transmitting only or principally yellow, since that is the only color common to the two; and where they overlap the purple bands we will have blue for the same reason. Thus the final result is a series of lines in substantially red, yellow and blue, and these lines are only half the width of the bands. It is of course advantageous from the point of view of the photographic result that the lines should be fine, while it is of advantage from the point of view of manufacture that the bands should be as wide as practicable. Thus both of these desiderata are served at the same time.

In Fig. 2, O, O indicate orange bands, P, P purple or magenta bands and G, G green bands as before; but these bands are put on so as to overlap for only one third of their width. The result is that the lines produced have only one third of the width of the bands. Moreover as each band is left uncovered for one third of its width, we have lines in six colors, i. e., red, orange, yellow, green, blue and purple, though only three are applied. It will be noticed that purple is optically scarcely distinguishable from violet, so that we have here practically the complete spectrum. The principal advan-

tage of this over the method of Fig. 1, is that the bands are still wider and there are no bands with contiguous edges.

If it is desired to obtain from the overlapping bands resulting lines in orange-red, green, and blue-violet, which are the colors most largely used in the established processes, this can be done by the method illustrated in Fig. 3. In this case the applied colors are blue-violet-red, or magenta as before; red-orange-yellow-green, or a color that will appear predominantly orange-yellow; and green-blue-violet, or to the eye blue-green.

The range of the spectrum covered by these three applied colors respectively should be approximately for the blue-green, from $\lambda 3,900$ to $\lambda 5,800$; for the orange-yellow from $\lambda 4,800$ to $\lambda 7,000$; and for the magenta, from $\lambda 3,900$ to $\lambda 4,900$ and from $\lambda 5,700$ to $\lambda 7,000$. The resultant lines will have the following color values: for the blue-violet $\lambda 3,900$ to $\lambda 4,900$; for the green $\lambda 4,800$ to $\lambda 5,800$; and for the orange-red $\lambda 5,700$ to $\lambda 7,000$.

My invention is not limited to the use of any particular dyes, as there are many suitable dyes commercially available.

Fig. 4 illustrates a simplification of the method of Fig. 2. In this case, in order to reduce the number of applied colors from three to two, the colors used are minus red-orange-yellow (i. e., such a color as will transmit all rays but those from the red end of the spectrum to and including yellow) and minus blue-violet (or a color that will transmit all rays except blue and violet).

The overlapping of these bands will give green, since this is the only color common to both, so that with only two applied colors we have red-orange-yellow, green and blue-green. To give the best result, the colors chosen, although they must contain green, should be somewhat weak in this color. This is illustrated by the spectra of these two colors given in Fig. 5, in which the intensity of the color is indicated by the ordinate of the curve. It will be noticed in Fig. 4, that the green recurs twice as frequently as the other colors. Thus the weakness in this color which is necessary in order to bring out the other colors, is compensated for by providing a greater area for the passage of green light.

Fig. 6, is a modification in which two series of bands at right angles are used, giving squares instead of lines of color. In this case one series of bands consists of red-orange-yellow and green-blue-violet respectively and the other series consists of orange-yellow-green and blue-violet-red respectively. The resultant squares are of red, green, blue-violet and orange-yellow.

It is to be understood that color screens made according to my invention may be used

either between the glass plates or celluloid film and the sensitive emulsion or as a separate taking or viewing screen.

It will now be seen that my invention provides a color screen that can be applied to either glass plates or celluloid films, including films for the production of moving pictures, by simple mechanical means, giving a cheaper and better method of photography in colors than any heretofore known.

In effect, I obtain a screen of substantially monochrome colors by the use of polychrome colors, subtractively applied (although additively employed in the subsequent photography) thus obtaining rich and natural rendering without the liability of black spots or other defects.

Having now described my invention, what I claim is:

1. A photographic color screen composed of colored bands having overlapping spectra. 85
2. A color screen composed of colored bands having color values in common.
3. A photographic color screen comprising two or more series of bands, said bands having color values in common. 90

4. A photographic color screen comprising two or more series of bands each band covering a range of the spectrum including two or more of the prismatic colors.

5. A photographic color screen comprising two or more series of overlapping bands of color. 95

6. A photographic color screen comprising two series of bands of color applied with a clearance between and a third series of 100 bands of color applied so as to overlap the two bands first mentioned.

7. A photographic color screen comprising a series of bands transmitting principally red, blue and violet light, a second 105 series of bands transmitting principally green, blue and violet light, and a third series of bands transmitted principally red, orange, yellow and green light.

8. A photographic color screen comprising 110 a series of bands transmitting principally red, blue and violet light, a second series of bands transmitting principally green, blue and violet light and a third series of bands transmitting principally red, orange, yellow 115 and green light, said bands being applied so as to overlap.

9. A photographic color screen comprising a series of parallel bands transmitting principally red, blue and violet light, a second 120 series of parallel bands transmitting principally green, blue and violet light and a third series of parallel bands transmitting principally red, orange, yellow and green light, said bands being applied in regular 125 sequence so as to overlap for one third or more of their width.

10. A photographic color screen compris-

ing two or more series of parallel bands of color applied with non-contiguous edges.

11. A photographic color screen comprising two or more series of parallel overlapping bands of color applied with non-contiguous edges.

12. A photographic color screen comprising two or more series of parallel overlapping bands of color, such bands where they overlap being in direct contact.

13. A photographic color screen comprising two or more series of parallel overlapping bands, said bands applied with non-contiguous edges, such bands where they overlap being in direct contact.

14. A photographic color screen comprising a series of bands transmitting principally blue, violet and red light, a second series of bands transmitting principally green, blue and violet light and a third series of bands transmitting principally red, orange, yellow and green light, said bands applied with non-contiguous edges.

15. A photographic color screen comprising a series of bands transmitting principally blue, violet and red light, a second series of bands transmitting principally green, blue and violet light, and a third series of bands transmitting principally red, orange, yellow and green light, said bands applied with overlapping, noncontiguous edges, such bands where they overlap being in direct contact.

16. A photographic color screen comprising two or more series of transparent polychrome bands, said bands being applied subtractively.

17. A photographic color screen comprising a plurality of polychrome bands, said bands being applied so as to produce by subtraction the effect of substantially monochrome bands.

18. A photographic color screen comprising a plurality of polychrome bands, said bands being applied so as to produce by subtraction the effect of bands transmitting light covering a narrower range of the spectrum than that covered by said applied bands.

19. A photographic color screen comprising a plurality of transparent colored bands, each of said bands being adapted to transmit two or more of the prismatic colors, adjacent bands being super-posed for a part of their width.

20. A photographic color screen comprising a series of transparent bands transmitting principally red, blue and violet light, a second series of transparent bands transmitting principally red, orange, yellow, and green light, the bands of said second series overlapping those of said first series for part of their width, whereby a series of bands transmitting principally red light is pro-

duced and a third series of transparent bands 65 transmitting principally green, blue and violet light, the bands of said third series overlapping those of said second series for part of their width, whereby a series of bands transmitting principally green light 70 is produced, the bands of said first series overlapping those of said third series for part of their width whereby a series of bands transmitting principally blue and violet light is produced.

21. The method of preparing a photographic plate for photography in colors which consists in applying bands adapted to transmit polychromatic light, said bands being overlapped in accordance with a definite pattern, whereby resultant bands are produced adapted to transmit light of a narrower range of color values than said applied bands.

22. The method of preparing a color 85 screen for photography in colors which consists in applying two or more series of bands, said bands being composed of transparent colloidal material, each of said series being dyed a color adapted to transmit polychrome 90 light rays, said bands being overlapped without contiguous edges according to a definite pattern, whereby resultant areas are produced adapted to transmit light of a narrower range of color values than said applied bands.

23. In a system of color photography, a color screen composed of colors adapted to be super-posed, whereby the difficulty of accurately registering the applied colors is 100 avoided.

24. In a system of color photography, a color screen composed of overlapping bands of color, whereby the resultant bands are narrower than the applied bands.

25. In a screen for color photography composed of applied colored bands any two of which may be super-posed without producing total absorption.

26. A photographic color screen comprising a series of bands transmitting principally a light from $\lambda 3,900$ to $\lambda 5,800$ inclusive; a second series of bands transmitting principally light from $\lambda 4,800$ to $\lambda 7,000$ inclusive; and a third series of bands transmitting principally light from $\lambda 3,900$ to $\lambda 4,900$ inclusive and from $\lambda 5,700$ to $\lambda 7,000$ inclusive.

27. A photographic color screen comprising a series of bands transmitting principally light from $\lambda 3,900$ to $\lambda 5,800$ inclusive; 120 a second series of bands transmitting principally light from $\lambda 4,800$ to $\lambda 7,000$, the bands of said second series overlapping those of said first series for part of their width, whereby a series of lines transmitting principally light from $\lambda 4,800$ to $\lambda 5,800$ inclusive are produced and a third series of bands transmitting principally light from $\lambda 3,900$ to $\lambda 4,900$ inclusive.

to λ 4,900 inclusive and from λ 5,700 to λ 7,000 inclusive, the bands of said third series overlapping the bands of said second series for a part of their width, whereby a series of 5 lines transmitting principally light from λ 5,700 to λ 7,000 is produced, the bands of said third series overlapping the bands of said first series for part of their width

whereby a series of lines transmitting principally light from λ 3,900 to λ 4,900 is produced.

In witness whereof I have affixed my signature hereto this fifth day of February, 1920.

KENNETH E. STUART.
